UNITED STATES PATENT OFFICE.

WILLIAM E. MORTRUEDE, JR., OF SEATTLE, WASHINGTON, ASSIGNOR OF ONE-FOURTH TO CHARLES W. LITTLEFIELD, ONE-FOURTH TO PHILIP T. MOLLEUR, AND ONE-FOURTH TO DAN C. BROWNELL, ALL OF SEATTLE, WASHINGTON.

ELECTROLYTIC-CELL BATTERY.

Application filed August 13, 1924, Serial No. 731,703. Renewed October 26, 1925.

To all whom it may concern:

Be it known that I, WILLIAM E. MORTRUEDE, Jr., a citizen of the United States of America, and resident of the city of Seattle, in the county of King and State of Washington, have invented certain new and useful Improvements in Electrolytic-Cell Batteries, of which the following is a specification.

10 My invention relates to electrolytic cells and consists of the novel type of construction employed which contributes to cheapness in first cost, effectiveness in sealing of the same, and convenience in operation of 15 assembling, opening, and closing the same.

The object of my invention is to contribute to these features of advantage and to make a cell which may be multiplied in numbers to constitute a battery of cells, which battery shall be a unitary structure which is 20 convenient in handling and effective when in use.

The features of my invention which are novel and upon which I desire to secure a 25 patent may be determined from an inspection of the drawings, together with a study of the following specification and claims.

The drawings illustrate cells made in accordance with my invention, the same being 30 of the type of construction which I now prefer to use.

Figure 1 is a top or plan view in which certain parts, the cover and the holding down means, have been removed to better 35 show the construction of the other parts.

Figure 2 is a side elevation, partially in section, of a certain number of cells of the battery.

Figure 3 is a transverse section of the 40 upper part of a cell, showing particularly the manner of securing the covers in place.

The general character of the construction employed is that of two side walls and a bottom secured permanently together in exact relationship, said side walls and bottom being provided with a series of channels extending across the bottom and vertically on the side walls, in which channels are placed diaphragm plates which divide the 45 space between the side walls into a series of individual cells. The preferred manner of construction of these side walls and bottom is to employ an exterior wood frame or wall, 1, and a lining or inner layer 1' of cement

or concrete. A series of channels 10 of material width extend across the bottom and up the inner faces of the side walls. 55

Against the side walls of these channels are placed diaphragm plates 3, these being arranged in pairs one against each of the opposite side walls of each channel. These diaphragm plates are made of a material which is capable of standing the action of the solutions employed, the gases developed, and the electrical current. A preferred material for this is a commercial asbestos plate. These plates 3 are made of a width such that when placed in the channels 10 they will extend entirely across the space between the side walls and to the bottom of 70 the channels or grooves in which they are placed. They are also of such a length as to extend throughout the vertical height of the cells. If, however, it is not found practical to obtain sheets of sufficient length for 75 this purpose, each of the diaphragms formed by these plates may be made of more than one piece, the edges being tightly abutted together.

To secure these plates in place, wedging 80 members are employed which tightly fill the spaces between the two adjacent diaphragm plates and lie in the grooves or channels formed in the walls. For the vertical portions of the grooves which are in the side 85 walls two tapered wedging members 4 are employed, and with these a thin protective strip 40, the latter being placed in contact with one of the diaphragm plates 3. In placing these wedging members, one of the 90 tapered wedges 4 is put in position against one of the diaphragm plates and the protective strip 40 against the other. The other wedge is then put in position and driven home. By this method of assembling the 95 sliding movement of the wedge which is being driven is not against the surface of the diaphragm plates and such plates are, therefore, protected against injury. Between the lower ends of each pair of diaphragm plates 100 a block 41 of such size that when it is driven in place it will snugly fit in the space, may be employed.

These wedges, when the cells are put into use, are subjected to the swelling action of the liquids contained in the chambers formed thereby, and in this way the edges of the diaphragm plates are squeezed powerfully 105

against the shoulders formed by the side walls of the channel so as to secure gas-tight joints.

The individual cells thus formed are provided with individual covers. The covers for the cells formed by the space between the adjacent channels, consists of a block or short piece of board 5 which is also provided with an undersurfacing plate 50 of a material which will stand the gas and liquid of the cell. This may be of an asbestos material of the same character as is employed for the diaphragm plates 3.

The cover 4 is made to fit closely between the upstanding edges of the diaphragm plates 3. The covers for the cells which are formed between the two diaphragm plates of each channel is of a wedging character similar to that employed to secure the vertical edges of the diaphragm plates. This consists of two wedges 4 and a protecting strip 40, these being identical in construction with those employed for securing the vertical edges, except that they are of less length. These wedge the diaphragm plates 3 tightly against the side edges of the covers 5 of the cells at each side, and therefore secure gas-tight joints across the upper end edges of the diaphragm plates. As the cells which are covered by the wedge members 4 are intended to hold a salt solution in the process for which these cells were particularly designed, a protective covering as of asbestos plate for these cells is unnecessary. If, however, the cells were to be employed in any process where such a covering is desirable, such covering may be employed.

At the outer side of each side wall of the cell battery are placed vertical bars or beams 40 6. These project above the upper edge of the battery a sufficient distance so that they may be employed in conjunction with the transverse tie rods 60 as a means for securely holding the covers down upon the cells. The transverse tie or connecting rods 60 at the upper side of the battery is placed some little distance above the upper surface of the cell covers. Bars 7, which may be of wood, extend lengthwise of the battery, one at each side thereof. These bars preferably are cut into short sections, each section being of such a length as to cover one or more of the cells, preferably two or three cells. Preferably also, the ends of these bars are cut 55 on a bevel as shown at 70. They bear against the under side of the tie rods 60. The covers for the individual cells are secured down by the insertion of wedges as 71 between the under surfaces of the bars 7 and the top of the cover plates. These may be driven into place and thus will forcibly hold the covers down so as to secure gas-tight joints.

By making the bars 7 short, and further by cutting them beveled on the ends, they 65 may be removed from a portion only of the

cells at one time, and by reason of the beveled cut of the ends, they may be freed from engagement with one of the rods 60 without in any way disturbing the holding-down effect of said rod upon the adjacent bar covering the adjacent cells of the series.

Anodes 8 and cathodes 80 may be of any suitable material found best adapted for use in the particular electrolytic process employed. These are secured to the covers 5 and each pair, anode and cathode, are connected by a buss bar 81. This type of construction forms an equal number of the small cells 9 and 90, these alternating in position and being separated simply by the diaphragm plates 3.

In the manufacture of caustic soda by these cells, the cells 9 would be the cells containing the salt solution. These are supplied with the salt solution through pipes 30 which are connected up with the headers so that the level of the solution would be the same in all the cells. The cell 90 which contains the anode will have chlorine released therein by the electrolytic action taking place. The other cell 90 which contains the cathode will have hydrogen liberated therein. Pipes as 91 connected with the cells in which hydrogen is released, will convey the hydrogen to any point desired, while other pipes 92 connecting with the other of the cells will convey the chlorine to any suitable point. The cells from which the hydrogen is released will eventually contain a caustic soda solution which may be drawn off through pipes 93, each of which is controlled by a valve.

The above type of construction, while being cheap to construct, will be found effective and reasonably durable. The particular type of construction employed makes them easy of access for any and all purposes and as well, makes a tight and effective cell.

What I claim as my invention is:

1. An electrolytic cell battery having a bottom and side walls provided at intervals with channels each extending across the inner faces of the bottom and the side walls, diaphragm sheets fitting against each side wall of said channels and extending across the cell, and securing members wedging in said channels between the edges of the diaphragm sheets.

2. An electrolytic cell battery having bottom and side walls common to all cells of the battery, the inner faces of bottom and side walls having channels cut therein, diaphragm sheets fitting against the side edges of said channels and extending between opposite side walls, wedging members fitting between the edges of said diaphragms within said channels, cover plates for the compartments formed between the said channels and wedging members fitting between the upper edges of the diaphragm sheets of

each channel and forming a cover for the compartment between said diaphragm sheets.

3. A battery of electrolytic cells having continuous bottom and side walls which on their inner faces have channels extending across the bottom and up each side, diaphragm plates secured against the opposite side faces of said channels and dividing the space between the walls into a series of cell chambers, cover members for each of said chambers, bars extending lengthwise of the battery over said covers, means for anchoring said bars from the walls of the battery, and wedges insertable between said bars and the covers.

4. A battery of electrolytic cells joined in a continuous series of cells, covers for the

individual cells, holding-down bars each extending over a limited number of cells, means for anchoring said bars from the cell walls, and wedges insertable between said bars and the cell covers.

5. A battery of electrolytic cells joined in a continuous series of cells, covers for the individual cells, holding-down bars each extending over a limited number of cells, said bars being cut with beveled meeting ends, cross bars extending over the ends of the holding down bars and anchored to the cell walls, and wedges insertable between said holding-down bars and the cell covers.

Signed at Seattle, King County, Washington, this 23rd day of July 1924.

WILLIAM E. MORTRUDE, JR.
